(57) **CLAIM**

The ornamental design for a corrugated envelope, as shown and described.

DESCRIPTION

FIG. 1 is a front perspective view of a corrugated envelope showing the new design in a folded configuration; FIG. 2 is a right elevation view thereof; FIG. 3 is a left elevation view thereof; FIG. 4 is a top plan view thereof; FIG. 5 is a bottom plan view thereof; FIG. 6 is a front elevation view thereof; FIG. 7 is a back elevation view thereof; FIG. 8 is a front perspective view of the corrugated envelope in an unfolded configuration; FIG. 9 is a right elevation view thereof; FIG. 10 is a left elevation view thereof; FIG. 11 is a top plan view thereof; FIG. 12 is a bottom plan view thereof; FIG. 13 is a front elevation view thereof; and, FIG. 14 is a back elevation view thereof.

The broken lines shown in the figures illustrate portions of the corrugated envelope that form no part of the claimed design. The break lines in the drawings are not part of the claimed design and represent that no particular length is claimed.

1 Claim, 10 Drawing Sheets
